MOLDED HOLLOW SHOE FORM

Louis W. Reinhardt, Brockton, Mass., assignor to
 George E. Belcher Company, Stoughton, Mass.,
 a corporation of Massachusetts

Application March 15, 1940, Serial No. 324,138

6 Claims. (Cl. 12—128)

My present invention relates to improvements in hollow shoe forms and to methods of making the same.

Molded hollow shoe forms of buckram or like sized stock have been well accepted. One of the problems of the manufacturer has been to provide on an economical basis such shoe forms sufficiently rigid for use and it is with this general problem that my present invention is immediately concerned.

The cost of molded shoe forms of the type under consideration depends, to a considerable extent, on the stock used. Buckram, as is well known, consists of a plurality of sized layers of textile stock and its cost depends in part on the number of layers of which the sheet is composed. While it is possible to procure stock of sufficient thickness to establish strong molded forms, for practical purposes, it is desirable to use less expensive material and according to my invention to add internal reinforcements where needed to provide the desired strength.

The addition of such reinforcements must be effected without the development of hard lines, defining on the exterior wall of the form, the edges of the reinforcement. Such lines would not only be objectionable because the desired smooth surface of the form would be destroyed, but also because when inserted in footwear the surface of the shoe upper would likewise be affected.

In accordance with my present invention, I am able to provide locally reinforced shoe forms in which such lines are eliminated and to accomplish this result without an objectionable increase either in the cost of the material or in the cost of manufacture.

In the accompanying drawing, I have shown illustrative embodiments of my invention from which the several novel features and advantages of shoe forms in accordance with my invention and the methods of their manufacture will be readily apparent. In the drawing:

Fig. 1 is a general view of a typical shoe form in accordance with my invention.

Fig. 2 is a bottom view of the shoe form shown in Fig. 1 partly broken away to show the internal local reinforcement.

Fig. 3 is a view of a last with the shaped reinforcement broken away to show details of the construction of the last.

Fig. 4 shows in perspective the reinforcement removed from its last.

Fig. 5 is a view similar to Fig. 4 showing a shoe

form shaped over the last and the reinforcement, and

Fig. 6 is a view of a modification of my invention.

5 It will be appreciated that shoe forms of the general type with which I am concerned are made of sized stock such as buckram cut out in blanks. When moistened, such stock may be shaped over a last from which it is removed and 10 finished after it has dried.

In Fig. 1 I have shown a shoe form in accordance with my invention having a reinforcement 2 for its rear part. The form 1 and the reinforcement 2 include integral sole flanges 3 and 15 4 respectively.

In the manufacture of the form shown in Fig. 1, the moistened sized blank from which the reinforcement 2 is established, is shaped over the cone 5 of the last 6 to which it adheres because 20 of its sizing. The moistened sized blank from which the form 1 is established is then molded over the last 6 and over the reinforcement 2 to which it becomes bonded.

In order to avoid any noticeable lines caused 25 by the extra thickness of the form 1 through its reinforced area, I form the lasts 6 with a recess 7 in the zone to be occupied by the reinforcement 2. The depth of the recess 7 is determined by the thickness of the stock employed so that 30 the reinforcement 2 when shaped with its front edge abutting the shoulder 8 is flush with the last and defines a smooth surface ensuring the desired external smoothness of the finished form.

35 Preferably, the reinforcements are cut out and shaped so that their rear edges coincide with the rear edges of the forms. In practice, the rear edges of completed forms in accordance with my invention are trimmed after the dried forms are removed from their lasts, and springs or toggle 40 units 9 or the like are then united to the inside of the sole flange 3.

In accordance with my present invention, I 45 may also, as shown in Fig. 6, unite a molded shoe form 11 with its molded reinforcement 2 by rivets 12. The rivets 12 preferably have a smooth flattened (rounding) head and a pair of prongs that can be tightly clinched through the inner surface of the preformed reinforcement band 2 to draw it snugly to and against the inner face 50 of the cone area of the more rigid shell like upper member 11. This causes the low flat head of the rivet to be substantially in the plane of the outer surface of the form and thus be entirely free from any tendency to mark the lining of a shoe in which it is inserted.

The form 11 and the reinforcement 2 may be of the same stock and are each separately formed and dried. They are then assembled as by rivets 12 with the first rivet being located through the cone portions of the form and reinforcement respectively. Other rivets are then set, preferably in pairs, one on each side of the form to ensure that the reinforcement 2 is evenly disposed in desired relation to the form 11 and another pair is employed to interconnect the flanges 3 and 4. 10 Because of the relatively greater strength of the form 10, the reinforcement 2 is drawn in assembly snugly against the interior surface of the form 10 without interfering with the desired smooth exterior surface of the completed form. Because of this fact, in this embodiment of my invention, the shoe form 10 and the reinforcement 2 do not have to be made on the lasts shown in Figs. 3 and 5, but may be made on identical lasts of any type.

Because of the relatively small amount of stock required for the reinforcement of forms and because the completed reinforced forms have a smooth surface, shoe forms in accordance with my invention are well adapted for 25 economical manufacture and well suited for satisfactory service.

What I therefore claim and desire to secure by Letters Patent is:

1. A reinforced last molded hollow shoe form 30 including an upper and an integral sole flange, a reinforcement of like stock for the rear part of said form interior, comprising a preformed band of the area and figure of the rear interior marginal zone at the rear of the form including 35 the cone and its laterally extended side portions to and including their sole flanges, means uniting said upper and said reinforcement, the exposed surface of said form having a normal smooth contour unbroken by ridge lines outlining the reinforcement.

2. A reinforced last molded hollow shoe form including an upper having a rear edge and an integral sole flange, an interior reinforcement

5 of like stock for the rear part of said form having a rear edge and including flange portions, means uniting said upper and said reinforcement with their rear edges coinciding, the exposed surface of said form having a normal smooth contour unbroken by ridge lines outlining the reinforcement.

3. The shoe form of claim 1 in which the uniting means are rivets.

4. The shoe form of claim 1 in which the uniting means is sizing.

5. A hollow shoe form comprising an upper including integral sole flange, a reinforcement for the rear part of said upper interior, comprising a preformed band of the area and figure of the rear marginal interior zone at the rear of the forepart, including the cone and its laterally extended side portions to and including their inturned sole flanges, said upper and said reinforcement being of sized textile stock, molded and dried, and means to unite said upper and said reinforcement, said uniting means comprising rivets, said rivets being disposed through the cone, the sides and the flanges of said upper and said reinforcement.

6. In a last-molded hollow shoe form, including an upper having an unfolded rearward edge and integral sole flange, said upper and said sole flange comprising a single layer of sized plural laminations of textile stock in cementitious union and a reinforcement of like stock for the rear part of said form within the upper portion of the form and having its rearward edge coincident with that of the upper portion of the form and its forward edge extending into the instep area of said form and cementitiously united to the inner surface of the form upper and wholly below its normal plane of last molding, whereby the outer surface of said upper presents the smooth continuous contours of the last without ridge line across its surface adjacent the zone of its reinforcement.
